UNITED STATES PATENT OFFICE

ARMOND G. ROSSIG, OF NEW YORK, N. Y.

DESIGN FOR AN ELECTRIC CANDLE LAMP STAND

Application filed November 28, 1930. Serial No. 37,826. Term of patent 3½ years.

To all whom it may concern:

Be it known that I, ARMOND G. ROSSIG, a citizen of the United States and residing in the city, county and State of New York, have invented a new, original, and ornamental Design for an Electric Candle Lamp Stand, of which the following is a specification, reference being had to the accompanying drawings, forming part thereof.

In the drawings:

Fig. 1 is a perspective view of an electric candle lamp stand and

Fig. 2 is a diagrammatic top plan view.

The design comprises an elongated rectangular base having its central portion stepped up so as to provide a central elevated

platform and four intermediate step-like platforms arranged two at each side of the central platform. An imitation tree rises centrally from the central platform. Two electric candles, one at each side of the central tree, rise from the two adjacent step-like platforms. Two imitation trees, one at each side of the central tree, rise from the next two adjacent step-like platforms. And two electric candles, one at each side of the central tree, rise from the opposite end portions of the base.

I claim:

The ornamental design for an electric candle lamp stand, as shown and described.

ARMOND G. ROSSIG.
